SAMUEL B. DODGE, OF ROSLYN, ASSIGNOR TO HIMSELF AND
DANIEL D. WINANT, OF BROOKLYN, NEW YORK.

Letters Patent No. 90,642, dated June 1, 1869.

IMPROVED FORGING-HAMMER.

The Schedule referred to in these Letters Patent and making part of the same.

To all whom it may concern:

Be it known that I, SAMUEL B. DODGE, of Roslyn, in the county of Queens, and State of New York, have invented, made, and applied to use, a certain new and useful Improvement in Forging-Hammers; and I do hereby declare the following to be a full, clear, and exact description of the said invention, reference being had to the annexed drawing, making part of this specification, wherein—

Figure 1 is a plan of the said machine complete, and
Figure 2 is a side elevation of the same.

Similar letters denote the same parts.

The object of this invention is to furnish a forging-hammer that can be worked by hand much more effectively and with less labor than the ordinary sledge-hammer, and the same machine can be run by steam or other power, when that is available, thus making a machine that can be employed in either large or small-smitheries.

My invention consists in a hammer, mounted so that its fulcrum can be adjusted vertically to keep the face of the hammer parallel to the anvil at any desired distance, in combination with a spring-connection to a crank-pin, that can be adjusted, and so that the revolution of the crank-pin shall operate the hammer with a blow similar to that given by the human arm, and said yielding connection between the hammer and crank-pin, allows for the different thicknesses of material being forged.

In the drawing—

a is the frame, carrying the shafts of the driving-pulley *b*, and *c* is a wheel, to which a crank-handle is applied, so that the machine can be driven by hand or by power.

c' is a belt to the pulley *d*, on the shaft *e*, and *f* is a tightening-pulley, operated by the treadle *g*, so that the belt can be allowed to slip more or less, and thereby the speed of the blows of the hammer be regulated.

On the end of the shaft *e* is a disk or face-plate, *h*, carrying the crank-pin *i*. This may be moved into either of the holes 1 2, in the said disk *h*, so as to regulate the extent of movement given to the hammer *k*.

The handle *l*, of the hammer, is provided at its back end with a broad plate or disk, *l'*, that occupies a slot in the vertical standard *m*, and through these the fulcrum-pin or bolt *3*, of the hammer, passes.

This construction prevents the hammer tilting side-wise, and keeps the face of the hammer parallel with that of the anvil *n*, transversely.

At the top and bottom of the standard *m* are the adjusting-screws and nuts *4* and *5*, connecting said standard to the supports *o* and *p*, and allowing the same to be raised or lowered so that the face of the hammer can be adjusted to be parallel, longitudinally, with the anvil *n*, at any desired distance, so as to allow for forging articles of different thicknesses, and with parallel surfaces.

The handle of the hammer is guided between the vertical standards *q*, and the sides of the handle should be shod with iron plates to prevent wear.

The connection, from the crank-pin *i* to the hammer *k*, is through the adjustable link *r* and spring *s*.

This link *r* can be lengthened or shortened as occasion may require, and the blow being communicated through the spring *s*, the parts yield to the greater thickness of metal, when the hammering of the same commences.

By this construction of hammer, the attendant has the entire control of the blow, to make it heavier or lighter, more or less rapid, and the hammer can be driven by manual or other power.

Shaping-dies may be applied to the hammer or anvil, or both, thus greatly increasing the usefulness of this hammer over the ordinary sledge.

What I claim, and desire to secure by Letters Patent, is—

The forging-hammer, provided with the standard *m*, carrying the fulcrum, and adjustable, as set forth, in combination with the revolving crank-pin *i*, adjustable link *r*, spring *s*, hammer *k*, and anvil *n*, as and for the purposes specified.

In witness whereof, I have hereunto set my signature, this 15th day of April, 1869.

Witnesses: SAMUEL B. DODGE.
F. SKILLMAN,
WILLET TITUS.
